AERATOR FOR FAUCETS OR THE LIKE

Harold Shames, 5 Agnes Circle, and Sidney J. Shames,
19 Agnes Circle, both of Ardsley, N.Y.

Filed Aug. 1, 1960, Ser. No. 61,588

Term of patent 14 years

(Cl. D91—3)

FIGURE 1 is a perspective view of an aerator for faucets or the like showing our new design;

FIGURE 2 is a side elevation of the same;

FIGURE 3 is a side elevation thereof as seen from the right of FIG. 2;

FIGURE 4 is a top plan view of the same;

FIGURE 5 is a bottom plan view of the same; and

FIGURE 6 is a view taken on line 6—6 of FIGURE 3. We claim:

The ornamental design for an aerator for faucets or the like, substantially as shown.
